[57] CLAIM

I claim the ornamental design for sensor controlled light, as shown and described.

DESCRIPTION

FIG. 1 is a front elevational view of a sensor controlled light showing my new design;

FIG. 2 is a left-side elevational view thereof;

FIG. 3 is a right-side elevational view thereof;

FIG. 4 is a rear elevational view thereof;

FIG. 5 is a top plan view thereof;

FIG. 6 is a bottom plan view thereof; and,

FIG. 7 is a front/right-side perspective view thereof.

The sensor controlled light is preferably battery powered with switch-selected manual and automatic modes of operation. The automatic mode uses a passive infrared sensor.
